GAS AND LIQUID SEPARATOR FOR OIL WELLS

Filed July 23, 1926

UNITED STATES PATENT OFFICE

LEO CHILLIE DUGGAN, OF SEDAN, KANSAS; PEARL DUGGAN ADMINISTRATRIX OF SAID
LEO C. DUGGAN, DECEASED

GAS AND LIQUID SEPARATOR FOR OIL WELLS

Application filed July 23, 1926. Serial No. 124,523.

This invention relates to improvements in separators for venting a gas from a liquid.

The primary object of this invention is the provision of an improved liquid and gas separator device preferably adapted for use in connection with oil well operation, for the purpose of segregating and releasing the water from a flowing body of gas.

A further object of this invention is the provision of an improved separating apparatus adapted for use in connection with the release of water from gas embodying an improved valve venting arrangement to permit the drip or flow of water from the gas as it exits from the well.

A further object of this invention is the provision of a compact separating apparatus embodying novel gas venting means and a novel float operated valve construction for automatically releasing water from a flowing body of gas.

Other objects and advantages of this invention will be apparent during the course of the following detailed description.

In the accompanying drawing, forming a part of this specification, and wherein similar reference characters designate corresponding parts throughout the several views,

Figure 1 is a side elevation of the improved separator.

Figure 2 is a longitudinal sectional view taken through the improved water drip or separating device.

Figures 3 and 4 are sectional views taken substantially on their respective lines in Figures 1 and 2 of the drawing.

In the drawing, wherein for the purpose of illustration is shown only a preferred embodiment of this invention, the letter A may generally designate the improved separator, which may comprise a housing or casing construction B, wherein a liquid vent or release valve C is mounted in automatically operated relation by novel float means D.

Referring to the casing construction B, the same preferably comprises a horizontally disposed relatively short hollow cylindrical shaped receptacle portion 10, providing a horizontally elongated compartment 11 wherein a body of water 12 is adapted to

settle. This body 10 is provided with a bottom opening 14, intermediate its ends, through which the water is adapted to be released by the valve mechanism C which will be subsequently disclosed. In a side wall of the body receptacle portion 10, the same is apertured at 15, through which a conduit 16 inlets; the conduit 16 being adapted to convey the initial body of gas from the well directly to the compartment 12; this body of gas, as is well understood, having droplets of water and moisture in suspension which may settle in the compartment 11 to provide the body of water 12. This inlet conduit 16 inlets into the compartment 11 at a point preferably above the valve construction C, so that the water will be maintained in a turbulent condition, to prevent settlements of deposits and sticking of the valve parts.

At one end thereof the housing construction B is provided with a vertically disposed gas receptacle or tube 20, which at the lower end thereof is welded at 21 at an angle of 45° to one end of the body 10, in such relation that the passageway or compartment 23 through the tube or barrel 20 communicates with one end of the receptacle 11, so that the water may rise from the compartment 11 for a short distance upwardly into the compartment 23 seeking its level, and so that the gas may vent through the body of settled water above the liquid level in the tube 20; the vertical tube 20 being of considerable height. At its upper end the tube 20 or barrel is provided with a welded conical shaped top wall 25, which is closed, and immediately below the wall 25 a tubular nipple 26 is welded in place, having a passageway 27 through which the gas vents and outlets into a conduit 29 which conveys the gas in its dry condition, to any suitable location.

Further referring to the housing construction B, the same includes a vertically disposed float tube or receptacle portion 35, which is preferably smaller in diameter and shorter than the gas riser portion 20, and which is connected on the top of the receptacle portion 10, intermediate the ends thereof, in slightly spaced but parallel relation with the barrel portion 20; the same having

a compartment 37 therein, which is in communication at its lower end with the top of the compartment 11 so that the water may enter in the lower portion of the compartment 37 to seek its level.

At a location above the liquid level in the receptacle portions 20 and 35, the same are connected by means of a horizontally disposed tubular connection 40, having a passageway 41 communicating between the compartments 23 and 37, for the purpose of venting the gas from the compartment 37 into the gas release and collecting compartment 23.

15 The end of the horizontal water receptacle portion opposite the end to which the vertical gas receptacle 20 is attached is provided with an annular attaching flange 45 to which a closure disc 46 is detachably connected by means of bolts or detachable members 48, to close this end of the compartment 11 in a detachable relation, so that when desired the cover 46 may be removed for access to the valve and adjacent details for cleaning, repair and the like.

In the lower portion of the receptacle body 10, adjacent to the closure 46, is provided a tubular nipple 49, which may be referred to as a drain nipple, over which a cap 50 is detachably mounted to normally close the same.

At the upper end the float tube or receptacle portion 35 is provided with an annular flange 55, over which a cover or closure disc 56 is detachably mounted as by bolts 57, to close the upper end of the compartment 37.

Referring to the valve construction C, the same includes a lever arm 60 pivoted at one end at 61 upon a bracket 62 which is mounted within the compartment 11 adjacent the end 40 of the receptacle portion 10 to which the gas receptacle or tube 20 is connected; the valve arm 60 extending longitudinally through the compartment 11 and at its other end being connected at 63 to the lower wall 64 of the vertical float tube 65 which is reciprocably mounted in the compartment 37 in a spaced relation with the inner walls of the float receiving tube or riser 35.

Intermediate the ends of the valve supporting arm 60 is provided a vertically depending needle valve 70, having a lower pointed end, and the upper end of which is bifurcated and pivoted at 71 upon the valve arm, as is illustrated in Figures 2 and 4 of the drawing.

A novel seat is provided for the valve 70. Depending in a welded relation from the lower portion of the receptacle portion 10 is a tubular nipple 73, about the opening 40, which is internally screw threaded at 75 for detachably receiving therein a tubular supporting screw 76, the lower end of which is provided with a wrench engaging head 77, and which is provided with an internally screw threaded passageway 78 therethrough

within which a bushing 79 is detachably mounted and extending upwardly into the opening 14. This bushing 79 is provided with an internally screw threaded passageway 82 therein, which detachably receives the internally screw threaded tubular valve seat member 86, the upper end of which is flared outwardly and which is provided with a cap 87 on the upper end thereof, apertured for slidably receiving the needle valve 70 in a guided relation therewith. In the member 86 is provided a downwardly constricted valve seat on which the point end of the needle valve is adapted to close off communication of the passageway 89 therethrough, to prevent the flow of water from the housing B. The opening 89 is of course properly calibrated according to the level to which the water should rise within the housing B, and the flared end of the valve seat tube 86 is laterally provided with openings into which the water passes into the passageway 89; these lateral openings of course being above the constricted valve seat on which the pointed end of the valve needle 70 closes. Incident to the provision of the plug 76 and the tubular bushing 79, the entire seat device may be detachably assembled by removing the plug 76 downwardly through the internally screw threaded opening 75, as is readily apparent.

In order to guide the float 65, a tubular guide rod 90 centrally extends through the float receptacle portion 35, the upper end thereof being screw threaded at 91 in detachable reception in the lower screw threaded end of a nipple 92 which extends upwardly from and upon the cover plate 56. The passageway thru the tube 90 is open to the passageway of the nipple 92 and the lower end of the tube 90 is open in the very lower portion of the compartment in the float body 65, immediately over the bottom 64, so that any water which may enter the float may be drained from the compartment thereof through the tube 90. On the upper end of the nipple 92 a stop cock 94 is mounted, to which suitable means may be applied for venting and withdrawing water or gas. Suitable brackets may be provided in the float for disposition about the guide rod 90, to guide movement thereof, but it is preferred to provide a reduced tubular neck 97 on the top wall 98 of the float body, provided with a passageway 99 through which the guide rod loosely extends for float guiding. The passageway 99 is open slightly to communicate the float compartment with the compartment 37 in the float receiving receptacle 35, so that pressure may be equalized in the compartment 37 and the compartment within the float itself, to permit proper functioning.

From the foregoing description of this invention the operation will be apparent. The gas is initially fed through the conduit 16 or the like, from an upper elevation to a

- lower elevation in the receptacle 10, entering the compartment 11 thereof. The water collects in the compartment 11 and rises to a predetermined level within the compartments 5 23 and 37 of the tubes or vertical receptacle portions 20 and 35 respectively, and at which time the float D will be buoyed up to open the needle valve 70 and release the water in a thin steam or drip through the passageway 89.
- 10 The gas passes into the compartment 23 both directly from the compartment 11 and from the float compartment 37 through the nipple or connection 40, and the dry gas is released through the conduit 29 at the top of the vertical gas receptacle portion 20, as can readily be understood.

All of the working parts of the apparatus, such as valve details and guide rod, are preferably of brass, and the float is preferably 20 of copper, although other materials may be used if desired.

Various changes in the shape, size, and arrangement of parts may be made to the form 25 of invention herein shown and described, without departing from the spirit of the same or the scope of the claims.

I claim:

1. A liquid separator, comprising a vertical water and gas receiving cylinder closed 30 at its upper end and with a dry gas outlet adjacent thereto and having a horizontal receptacle opening into its lower end into which water may settle, said receptacle having a bottom outlet opening intermediate its 35 ends, a gas inlet opening into the receptacle above said outlet opening for admitting gas from a well directly into the body of water for sustaining the water in a turbulent state, a gas tube rising from the receptacle adjacent 40 the cylinder and connected thereto intermediate the ends of both the cylinder and tube and above the water level of the same for venting gas from the tube to the upper portion of the cylinder, said tube having a closed 45 top, a lever pivotally mounted at one end in the receptacle adjacent the cylinder, and terminating at its free end beneath the tube, a float pivoted to the free end of the lever and extending upwardly in the tube and open 50 at its upper end near the top of the tube, and a valve carried by the lever over said outlet in the receptacle to control the outflow of water from the receptacle.

2. A liquid separator, comprising a vertical water and gas receiving cylinder closed 55 at its upper end and with a dry gas outlet adjacent thereto and having a horizontal receptacle opening into its lower end into which water may settle, said receptacle having a bottom outlet opening intermediate its 60 ends, a gas inlet opening into the receptacle above said outlet opening for admitting gas from a well directly into the body of water for sustaining the water in a turbulent state, a gas tube rising from the receptacle ad-

jacent the cylinder and connected thereto intermediate the ends of both the cylinder and tube and above the water level of the same for venting gas from the tube to the upper portion of the cylinder, said tube having a 70 closed top, a lever pivotally mounted at one end in the receptacle adjacent the cylinder, and terminating at its free end beneath the tube, a float pivoted to the free end of the lever and extending upwardly in the tube 75 and open at its upper end near the top of the tube, and a valve carried by the lever over said outlet in the receptacle to control the outflow of water from the receptacle, said receptacle being of cylindrical construction 80 and having an internally threaded tubular nipple depending from the outlet opening, a hollow supporting screw threaded in the nipple, a bushing threaded in the screw, a valve seat threaded in the bushing for receiving 85 said valve thereon, said valve seat being tapered downwardly for proportionately restricting the out flow proportionately to the rise and fall of the float, and a hollow guide rod mounted in the top of the gas tube and 90 extending into the float and opening at its lower end into the float and at its upper end opening to the atmosphere.
